UNITED STATES PATENT OFFICE.

ERNEST C. BENNETT, OF NEW YORK, N. Y.

ARTIFICIAL DENTURE.

1,074,345.

Specification of Letters Patent. Patented Sept. 30, 1913.

Application filed March 8, 1913. Serial No. 752,910.

To all whom it may concern:

Be it known that I, ERNEST C. BENNETT, a citizen of the United States, residing at New York city, county and State of New York, have invented certain new and useful Improvements in Artificial Dentures, of which the following is a full, clear, and exact description.

This invention relates to improvements 10 in artificial dentures and is more particularly concerned with a readily attachable and removable artificial bridge for use in connection with permanent end abutment teeth which, when in position, affords a very 15 snug fit and which combines simplicity of construction with ease of operation.

The present invention is described in detail in the following specification taken in connection with the accompanying drawings 20 illustrating preferable embodiments thereof.

In these drawings, Figure 1 is a view in rear elevation conventionally representing part of the gum with the bridge structure 25 of the present invention applied thereto. Fig. 2 is a similar view with the bridge removed. Fig. 3 is a transverse vertical section of Fig. 2. Fig. 4 is a view in end elevation of the bridge removed. Fig. 5 is a 30 horizontal section taken through the bridge on line 5—5, Fig. 1, as attached to permanent end abutment teeth. Fig. 6 is an enlarged detail view of the attaching means shown in Fig. 5 but of reverse form. Figs. 35 7 and 8 are views in top plan and end elevation respectively of a modified form of attaching means. Fig. 9 is a view similar to Fig. 5 illustrating another modified form of attaching means. Fig. 10 is a view similar 40 to Fig. 9 but showing a third modification of the attaching means. Fig. 11 is a view in front elevation of the spring latch holder shown in Fig. 10. Fig. 12 is a detail view of the spring latch shown in Fig. 10.

Referring to the drawings by numerals, and particularly Figs. 1-6, 1 designates conventionally a part of the gum and 2 permanent end abutment teeth between which the bridge of the present invention may be inserted. These abutment teeth form in effect anchorage teeth and are usually natural teeth. In the present instance they are preferably capped, crowned or otherwise prepared with inwardly projecting abutments 3 adapted to engage with the bridge and with the fastening means thereof.

While I prefer to provide the end abutment teeth with separate inwardly projecting abutments 3, these abutments may be extended and joined to form a bar 3^a (indicated in dotted lines in Fig. 2).

The bridge forming the subject-matter of this invention comprises a saddle portion 4 shaped on its under side to rest upon the natural gum between the permanent teeth 2 and carrying on its upper face one or more artificial teeth 5. Adjacent its ends, the saddle portion 4 is provided with recesses 6—7 adapted to receive the inward projections 3 of the end abutment teeth. 60 In case the bar 3^a is used in place of the spaced abutments 3, a slot will be provided extending longitudinally of the saddle and permitting the latter to fit over the gum and over this bar. The recess 6 is in the 65 form of a socket adapted to seat over its projection 3, while the recess 7 is in the form of a slot extending upwardly from the lower edge of the saddle, the upper edge of the saddle resting upon its projection 3. 70

Embedded in the material of the saddle, which in practice is quite hard and durable,

is a spring latch having one end 8^a firmly inserted in the body of the saddle adjacent one end and preferably so as to underlie the recess 6 therein and engage the under face of the projection 3 seated in said recess. This spring latch adjacent its other end is provided with a latching arm 8^b and with a finger piece 9 extending therefrom. The 85 latching arm is positioned within the recessed portion 7 of the bridge saddle so as to bring its upper face beneath the under face of the projection 3 resting within the recess. The spring material of the latch 90 member normally throws its latch arm inwardly to bring the same beneath the projection of the end abutment tooth. The finger piece 9 extends out to the rear of this end abutment tooth and may be readily moved 100 by the finger or by an instrument to retract the latch arm 8^a from said recess so that the bridge may be easily removed from the gum and its end abutment teeth for repair, cleansing, etc. When it is desired to again insert 105 the bridge between its end abutment teeth, it is only necessary to bring the recess 6 at one end of the bridge over a projection 3, retract the latch arm 8^a by means of the finger piece 9 and seat the other end of the 110 bridge over the opposite projection 3, the finger piece 9 when released permitting its

latch arm 8^a to spring in under the projection 3 and securely lock the bridge in place, the saddle resting on the gum and against the end abutment teeth and distributing pressure evenly upon said teeth and gum. The form of spring latch shown in Figs. 1, 4 and 5 may be reversed as illustrated in Fig. 6 and as will be obvious. This form of spring latch may be also modified somewhat in form, as illustrated in Figs. 7 and 8 wherein the end 10 of the latch is adapted to be firmly seated in the saddle of the bridge in a manner corresponding to the end 8 of the first form described. At its opposite end the latch is provided with an inwardly projecting latching arm 11 having its upper face shaped to correspond with the shape of the inward projection from the end abutment tooth with which it coöperates. This form of latch is also preferably provided with a finger piece 12 and is used in operation in a manner similar to that of the first form described.

In the two forms heretofore described, the inherent resiliency of the material of the latch arm has been utilized to normally project the latching arm of the latch into latching position. In Fig. 9 I have illustrated a further modification of the latching means wherein a latch member 13 is provided at its ends with complementary latch arms 14 and with a central inwardly projecting headed stud 15. This stud is seated in and moves longitudinally of a cylinder 16 within which is mounted a coiled spring 17 bearing against the head of the stud and normally moving the stud and the latch member with its latching arms 14 inwardly to bring these latching arms beneath the under faces of the inward projections 3 or the under face of a continuous bar structure, such as suggested in Fig. 2, the saddle portion 4 being provided in such event with an elongated groove in place of the recesses 6 and 7. The latch member 13 is also preferably provided with a finger piece 13^a by means of which these latching arms may be withdrawn from the saddle recesses to permit the removal of the bridge.

A still further modification is illustrated in Figs. 10-12 of the drawings, wherein a latch holder 18 is provided, this holder having arms 19 extending therefrom and embedded in the material of the saddle 4. The end of the holder 18 is in the form of a tubular casing through which the threaded end 20 of a latch member 21 extends, the opposite end of the latch member being provided with a latching arm 22 and with a finger piece 23. A nut 24 engages the threaded end 20 of the latch member and holds it firmly in its holder 18. The operation of this latching member is the same as that of the first form described. It has this advantage there-over, however. The provision of the nut 24

enables a latch arm which has been damaged or has become ineffective, to be removed and replaced by a new one without destroying or cutting away the material of the saddle portion of the bridge.

The removable bridge herein described, in addition to giving an equal distribution of pressure upon the teeth and gum, is interlocked with the end abutment or abutments so that it cannot be withdrawn from engagement therewith during mastication, as is the frequent trouble experienced with the removable bridges of the prior art. This is, of course, made possible by reason of the fact that the latch member or members are positioned to underlie the permanent abutments so that upward movement of the saddle or bridge portion which carries these latch members, is prevented by reason of the interlocking engagement of the latch member or members and the permanent abutment or abutments.

In all of the forms which have been described, two permanent end abutment teeth have been specified. It is not necessary, however, that such end abutments be both permanent teeth, as one of said abutments could be carried by a bar extension, for instance from a permanent end tooth; nor is the invention limited, in fact, to a bridge used in conjunction with two end abutments, but may be used in conjunction with a single end abutment, the movable latch member interlocking the bridge with this single-abutment.

What I claim, therefore, and desire to secure by Letters Patent is:

1. A removable artificial bridge for use in conjunction with a permanent end abutment comprising a removable saddle portion arranged to rest upon the natural gum adjacent such abutment and provided with an artificial tooth, and means carried by the bridge intermediate its upper and lower edges and movable transversely of the bridge for detachably interlocking said bridge with and against movement relative to said end abutment, said means including a movable latch member carried by the bridge.

2. A removable artificial bridge for use in conjunction with a permanent end tooth having a projecting abutment, comprising a removable saddle portion arranged to rest upon the natural gum adjacent such permanent tooth abutment and carrying an artificial tooth, means carried by said saddle portion arranged to interlockingly engage with and detachably hold said bridge to said abutment, said engaging means including a latch member carried by the saddle below said tooth and movable transversely of said saddle, and means normally holding said latch member in abutment engaging position.

3. A removable artificial bridge for use in

conjunction with a permanent end tooth having a projecting abutment comprising a removable saddle portion arranged to rest upon the natural gum adjacent said permanent tooth abutment and recessed to receive the same therein, said saddle portion carrying an artificial tooth, and means carried by said saddle portion positioned to interlock the same with said end tooth, said means including a spring latch member movable transversely of said saddle and having a portion normally positioned within said saddle recess at a point intermediate its upper and lower edges to underlie said permanent tooth abutment when received therein.

4. A removable artificial bridge for use in conjunction with permanent end teeth having projecting abutments, comprising a removable saddle portion arranged to rest upon the natural gum between such permanent teeth and recessed to receive said projecting abutments, an artificial tooth carried by said saddle portion, and retaining abutments carried by said saddle portion and positioned to engage said permanent project by said saddle portion, and retaining abutments comprising a movable bar of spring material having a latching portion normally positioned within a saddle recess to underlie the permanent tooth abutment received therein, said bar being provided with an extension whereby it may be moved to withdraw its latching portion from beneath said permanent tooth abutment and thereby permit the removal of the bridge.

Corrections in Letters Patent No. 1,074,345.

It is hereby certified that in Letters Patent No. 1,074,345, granted September 30, 1913, upon the application of Ernest C. Bennett, of New York, N. Y., for an improvement in "Artificial Dentures," errors appear in the printed specification requiring correction as follows: Page 1, line 83, for the reference-numeral "8" read 8; page 3, strike out line 26; and that the said Letters Patent should be read with these corrections therein that the same may conform to the record of the case in the Patent Office.

Signed and sealed this 14th day of October, A. D., 1913.

conjunction with a permanent end tooth having a projecting abutment comprising a removable saddle portion arranged to rest upon the natural gum adjacent said permanent tooth abutment and recessed to receive the same therein, said saddle portion carrying an artificial tooth, and means carried by said saddle portion positioned to interlock the same with said end tooth, said means including a spring latch member movable transversely of said saddle and having a portion normally positioned within said saddle recess at a point intermediate its upper and lower edges to underlie said permanent tooth abutment when received therein.

4. A removable artificial bridge for use in conjunction with permanent end teeth having projecting abutments, comprising a removable saddle portion arranged to rest upon the natural gum between such permanent teeth and recessed to receive said projecting abutments, an artificial tooth carried by said saddle portion, and retaining abutments carried by said saddle portion and positioned to engage said permanent project by said saddle portion, and retaining abutments comprising a movable bar of spring material having a latching portion normally positioned within a saddle recess to underlie the permanent tooth abutment received therein, said bar being provided with an extension whereby it may be moved to withdraw its latching portion from beneath said permanent tooth abutment and thereby permit the removal of the bridge.
